Specification for Design.

Patented June 15, 1920.

Application filed February 24, 1920. Serial No. 360,996. Term of patent 7 years.

To all whom it may concern:

Be it known that I, OLNEY R. PAYNE, a citizen of the United States, residing at Philadelphia, in the county of Philadelphia and State of Pennsylvania, have invented a new, original, and ornamental Design for a Toy Garage, of which the following is a specification, reference being had to the accompanying drawing, forming a part thereof.

Figure 1 is a perspective end view of the "toy garage"; and

Fig. 2 is a similar perspective view looking to the opposite end thereof and with the doors open.

I claim:

The ornamental design for a toy garage as shown.

OLNEY R. PAYNE.
